UNITED STATES PATENT OFFICE.

HEINRICH MÜLLER AND KARL SPECKER, OF ST. GALLEN, SWITZERLAND.

HOLDER FOR SHEETS OF ALL KINDS.

No. 902,433.

Specification of Letters Patent.

Patented Oct. 27, 1908.

Application filed June 15, 1908. Serial No. 438,652.

To all whom it may concern:

Be it known that we, HEINRICH MÜLLER, a citizen of the Republic of Switzerland, residing at St. Gallen, in the Canton of St. Gallen, Republic of Switzerland, (whose post-office address is No. 14 St. Magnihalden, St. Gallen,) and KARL SPECKER, a citizen of the Republic of Switzerland, residing at St. Gallen, in the Canton of St. Gallen, Republic of Switzerland, (whose post-office address is No. 18 Harfenberg, St. Gallen,) have invented certain new and useful Improvements in Holders for Sheets of all Kinds; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of the invention is to provide a holder for sheets of all kinds of such novel and peculiar construction that the sheets may be grasped along the one or along the other edge or along both the edges of the pinching-bar, whereby the binding effect of the said bar may be increased when a pull is exerted on the sheets.

A further object of the invention is to provide a holder for sheets of all kinds provided with two supporting arms each of which having a fold into which the end of the counter-arm may be shifted.

This holder is suited for holding newspapers, but any other sheets *i. e.* cloths of banners or flags, curtains, draperies, fabrics, etc. may be securely held by the same.

In the drawing Figure 1 is an elevation of a holder constructed in accordance with the present invention. Fig. 2 is a side-view thereof. Fig. 3 is a sectional view on the line $x-x$ of Fig. 1. Fig. 4 is an elevation of a modification of the holder. Fig. 5 is a sectional view on the line x^1-x^1 of Fig. 4. Fig. 6 is an elevation of another form of construction and Fig. 7 is a sectional view on the line x^2-x^2 of Fig. 6.

The supporting bar c (Figs. 1, 2 and 3) is provided with a hollow h corresponding substantially to the cylindrical surface of the pinching-bar e , and also with a lateral ledge h^1 overlapping the hollow h . This

ledge h^1 partially overlaps also the pinching-bar e in the closed position and limits the swinging-movement of this bar. The hollow of the supporting bar c and the operative surface of the pinching-bar e are coated with a mixture consisting of glue and emery powder, in order to increase the gripping force of the holder. The supporting-bar c is provided with the usual eye c^1 for hanging the holder and with the usual handle (not shown).

The main-portion of the pinching-bar e is of semi-circular section (see Fig. 3), while the ends e^1 of the bar e are cylindrical and provided with ribbed sockets e^2 which serve as handles for actuating the pinching-bar e . The cylindrical end-portions of the bar e are placed in slots c^3 of the supporting-bar and have eccentric pivots e^3 carried by flat sockets e^4 placed in slots of the supporting-bar c .

The sockets e^4 permit the pinching-bar e not only to swing around the pivots e^3 but also to be moved laterally, whereby the insertion of the sheets into the holder is very much facilitated and the insertion of a large number of sheets therein permitted. The sockets e^4 allow furthermore an easy bringing of the pinching-bar e into the proper position on the supporting-bar c .

It is obvious that the sheets may be brought into the holder from both sides and that they may be pinched at both longitudinal edges of the pinching-bar e , by being pressed simultaneously between one edge of the pinching-bar and the wall of the slot h , and between the other edge of the pinching-bar e and ledge h^1 . When bringing the sheets from the left side (ledge side) into the holder, a pull exerted on the sheets will increase the pinching effect the pinching-bar being pressed still more tightly against the bar c and the overlapping ledge. A single sheet will be held in the same tight manner as a series of sheets. In order to render more difficult the opening of the pinching-bar e and the stealing of the sheets, a winged-screw f is provided and may be pressed on the outer face of the upper cylindrical portion e^1 of the pinching-bar e . An angle g is secured to the supporting-bar c and carries the nut i for the winged screw f . For opening the holder, the winged

screw *f* is lifted, whereupon the sheets may be removed or new sheets may be brought into the holder.

If the holder is used as a news-paper holder, two small metal-plates *g* are secured to the supporting-bar *c*. A metal-strip *r* having a fold *r*¹ in the center is linked to each plate *g*. When the holder is not used, the metal-strips *r* lie parallel to the bar *c* and the end of one strip *r* lies in the fold *r*¹ of the other strip, so that the strips support themselves mutually. However when the holder is to be used, the strips *r* are turned away from the bar *c*, so that they are perpendicular to the same and serve as a support for the sheets clamped in the holder. Instead of at the left side the overlapping ledge *h*¹ may also be at the right side of the holder.

20 The holder shown by Figs. 4 and 5 has a cylindrical supporting-bar *c* and four pinching-bars *e* of the described construction, so that four sheets may be individually held in the holder. Fig. 5 shows the bars in different positions.

The modification shown by Figs. 6 and 7 is suited for holding curtains, draperies, fabrics, cloths of banners or flags and the like.

The supporting bar *c* has two eyes for hanging the holder, from which the sheet *k* hangs down. The latter is pinched by the whole semi-circular surface of the bar *e* and between this bar and the overlapping ledge *h*¹. The more the sheet is pulled or stretched the more the pinching-bar is turned into the pinching position and the sheet kept, so that it will be fully impossible to pull out the sheet.

In curtains, banners etc. the pinching-bar *e* is embedded in a suitable manner in the roller or shaft, so that the holding device does not hinder the use of the curtain etc. The nailing down of the curtains, banners etc. on rollers and shafts is overcome by the present holding device.

Two or more pinching-bars may be placed side by side on one flat supporting bar. The sheet-support may also be movably secured to the supporting-bar by means of clasps.

50 The inner face of the overlapping-ledge may also be formed as a hollow.

What we claim is:

1. A holder for sheets of all kinds, comprising a supporting bar having a hollow for the sheets and an overlapping ledge, and a pinching-bar eccentrically pivoted in the supporting bar and having a pressure surface and means for actuating the bar, whereby the sheets may be pinched at one or at the other or at both edges of the pinching bar.

2. A holder for sheets of all kinds, comprising a supporting bar having a hollow for the sheets and an overlapping ledge and a pinching-bar eccentrically pivoted and

laterally movable in the supporting-bar, and having a pressure surface and means for actuating the bar.

3. A holder for sheets of all kinds, comprising a supporting bar having a hollow for the sheets and an overlapping ledge, and a pinching-bar eccentrically pivoted in the supporting-bar and having a middle portion of semi-circular section for pinching the sheets and cylindrical end portions for actuating the bar.

4. A holder for sheets of all kinds, comprising a supporting bar having a hollow for the sheets and an overlapping ledge, and a pinching-bar eccentrically pivoted in the supporting-bar and having a middle portion of semi-circular section for pinching the sheets and cylindrical end portions having ribbed sockets for actuating the bar.

5. A holder for sheets of all kinds, comprising a supporting bar having a hollow for the sheets, an overlapping ledge and flat sockets fitted in slots of the bar, and a pinching-bar having eccentric pivots freely carried by the said sockets, a pressure-surface and means for actuating the bar.

6. A holder for sheets of all kinds, comprising a supporting bar having a hollow provided with means for increasing the frictional contact with the sheets and an overlapping ledge, and a pinching-bar eccentrically pivoted in the supporting bar and having a pressure surface provided with means for increasing the frictional contact between the bar and the sheets and means for actuating the bar.

7. A holder for sheets of all kinds, comprising a supporting-bar having a hollow for the sheets and an overlapping ledge, a pinching-bar eccentrically pivoted in the supporting-bar and having a pressure surface and means for actuating the bar, and a support for the sheets formed of two hinged metal-strips, each having a fold into which enters the end of the counter-strip in the inoperative position.

8. A holder for sheets of all kinds, comprising a supporting bar having a hollow for the sheets and an overlapping ledge, a pinching-bar eccentrically pivoted in the supporting-bar and having a pressure surface and means for actuating the bar, and means for rendering more difficult the opening of the pinching-bar and the stealing of the sheets.

9. A holder for sheets of all kinds, comprising a supporting bar having a hollow for the sheets and an overlapping ledge, a pinching-bar eccentrically pivoted in the supporting-bar and having a pressure surface and means for actuating the bar, and a pressure screw supported by the supporting-bar and adapted to be pressed down on one end of the pinching-bar.

10. A holder for sheets of all kinds, com-

prising a supporting bar having a plurality of hollows for the sheets and a plurality of overlapping ledges and a plurality of pinching bars eccentrically pivoted in the supporting bar, each having a pressure-surface and means for actuating the bar.

In testimony whereof, we have signed our

names to this specification in the presence of two subscribing witnesses.
